UNITED STATES PATENT OFFICE.

HENRY MOECKER, JR., OF HOMEWOOD, AND THEODORE THOMPSON, OF HARVEY, ILLINOIS, ASSIGNORS TO AMERICAN STOVE COMPANY, OF ST. LOUIS, MISSOURI, A CORPORATION OF NEW JERSEY.

METHOD OF MAKING COOKING TOPS OR BURNER FRAMES FOR GAS RANGES OR THE LIKE.

Original application filed December 18, 1924, Serial No. 756,771. Divided and this application filed June 15, 1925. Serial No. 37,167.

This invention relates to improvements in the method of making cooking tops or burner frames for gas ranges or the like, being more specifically a cooking top of stamped steel in one piece so constructed that the maximum strength and durability is obtained by the minimum cost of manufacture for a given weight of material.

This invention is an improvement over cooking tops or burner frames as heretofore made in channel form and V-slotted or notched at their corners. A frame such as referred to appears in the F. G. Nicolaus Patent No. 1,178,259 of April 4, 1916. In frames of the Nicolaus type one or more pieces of channel iron are sometimes used and the corners when bent are either welded or the V'd or notched out portions are sometimes left slightly apart or open.

The object of the present invention is to provide a cooking top or frame stamped from a single piece of material which is very rigid and unbreakable and at the same time produce a frame in which the vertical joints adjacent the corners of the frame are flush, thereby producing a more simple, cheap and practical frame which is of great strength and durability and can be manufactured at the minimum cost both as to labor and material.

Another object of the invention is the novel manner of cutting or notching the corners of the frame blank whereby a smooth flush joint is made adjacent the corner of the frame in the finished article.

Another and further object of the invention is to provide a cooking top or frame for gas stoves or the like of a novel construction which is pleasing in appearance and at the same time possesses strength and durability and is cheap and simple of manufacture.

Other further objects, novel features of construction, and improved results will appear from the following description and accompanying drawings.

In the drawings:

Figure 1 is a perspective view of the stove frame or cooking top ready for application to a stove.

Figure 2 is a plan view of the blank from which the frame is made, the blank being shown prior to the bending operation.

Figure 3 is an enlarged detail perspective

view of one corner of the frame showing the manner of forming the joint adjacent the frame corner.

Figure 4 is a fragmentary enlarged sectional view taken on the line 4-4 of Figure 3 looking in the direction indicated by arrow.

Figure 5 is an enlarged fragmentary sectional view of the improved frame, the section being taken on the line 5-5 of Figure 3 looking in the direction indicated by arrow.

Referring now to the drawings in which like parts are designated by similar reference numerals throughout the description it will be seen that the frame is composed of one continuous piece of material. It has been found that steel is the preferable material to use but it will be readily understood that if desired other materials could be substituted to suit any particular use to which the principle of the invention is applied.

In the embodiment shown in the drawings and hereinafter described the frame is square but the principle of the invention can be applied to frames of other shapes and for frames for uses other than upon gas ranges.

When the blank has been stamped out from the material to be used its form is as appears in Figure 2 of the drawings. L-shaped notches are cut in the outer four corners of the frame blank, these notches leaving in the frame corners a short leg 10 and a longer leg 11. The particular reason for making one leg of the notch longer than the other will be given hereinafter.

The frame at its four inner corners is provided with semi-circular cut out portions 12 which join the inner perimeter of the frame in rounded corners 13.

The four sides or legs A, B, C and D of the frame are made of a sufficient width so that in the completed frame formed as appears in Figure 1 of the drawings each of the legs can be bent to form a top 14, an outer wall 15 and an inner wall 16. By forming the frame in this manner, it will be seen, as clearly appears in Figure 5 of the drawings, that the frame is of an inverted U-shape in cross section.

Prior to the bending or forming of the

blank to the frame shape a series of holes 17 are made adjacent the outer perimeter of the frame blank and a series of holes 18 are formed adjacent the inner perimeter of the blank. The holes 17 are for the purpose of receiving bolts (not shown) for fastening the frame to the range body while the openings 18 are for the purpose of receiving bolts or other suitable appliances (not shown) for supporting the gas burners in the frame or cooking top.

In bending or forming the blank into the finished frame as it appears in Figure 1 of the drawings the legs A, B, C and D are bent downwardly adjacent their inner edge in a line or plane running slightly inside of the extreme depth of the semi-circular cut out portions 12. It will be seen by referring to Figures 1 and 2 of the drawings that this will leave at the inner corners of the frame a short inner wall or flange 19.

The legs of the blank are then bent downwardly adjacent their outer edges in a line or plane slightly inside of the apex of the cut out portions at the outer corners of the frame blank. To complete the outer wall it is necessary to bend the longer leg portion 11 of the notched corners around and into the plane of the adjacent frame leg outer wall. This extending portion is designated in the drawings by a numeral 20 and will closely abut and lie flush with the outer frame wall. Due to the fact that the frame legs were bent downwardly adjacent their outer edge in a plane or line slightly inside of the apex of the notches the leg 11 does not reach the outer edge of the top 14 of the frame there being a space 21 between them. By forming the frame in this manner the corners are perfectly smooth and are slightly rounded.

It will be also seen that the outer edge 22 and the inner edge 23 of the top 14 of the frame are also slightly rounded rather than presenting a sharp definite edge.

From the foregoing it will be seen that the cooking top or frame is formed from a single piece of material and that in its completed form presents a frame which is pleasing in appearance as all of its edges and corners are slightly rounded and are smooth both as to appearance and touch. Furthermore the meeting edges or ends of the outer side walls are smooth and are not positioned immediately at the corners of the frame. It will be further seen that the semi-circular cut out portions 12 at the inner corners of the frame spread out into a pleasing contour to the eye in the finished frame.

It will be readily understood that the forming or the bending of the frame can be done by machine. The stamping out of the blank can likewise be done by machine as can also the drilling of the bolt holes 17

and 18. From this it will be seen that a frame made in accordance with this invention is cheap and simple of manufacture because of the machine work and additionally because there is no waste of material. Furthermore the frame possesses great strength and durability combined with a pleasing appearance.

By reason of folding or bending the inner and outer legs 15 and 16 of the frame on lines inside of the outer corner notches and the inner corner circular cut out portions a short or narrow wall portion 21 is formed adjacent the outer corners of the frame above the notches and the narrow inner wall portion 19 is formed at the inner corners of the frame. Due to these narrow wall portions it is possible to form the inner and outer corners of the frame without any puckering of the material which would present a rough and uneven surface. This feature of the construction of the frame is important for otherwise puckering would occur which would detract from the frame as will be readily understood. Furthermore it is possible, by reason of the circular cut out portions at the inner corners of the frame to make these corners in an arc or curve as clearly appears at 24 in Figures 1 and 3 of the drawings. As also clearly appears in the drawings there is no puckering at the outer corners of the frame.

Having thus described our invention, what we claim and desire to secure by Letters Patent, is:

1. The method of making a frame, comprising stamping the frame in one piece from a sheet of material, forming angular notched portions at the outer corners of the frame, forming circular cut out portions at the inner corners of the frame, bending the edges of the frame downwardly in a line inside of the notched corners, bending the inner edges of the frame downward on a line inside of the circular cut out portions, whereby the inner corners of the frame are rounded and the walls of each notched portion at the outer corners of the frame abut and a frame is formed which is substantially U-shaped in cross section.

2. The method of making a frame, comprising stamping the frame in one piece from a sheet of material, forming angular notched portions at the outer corners of the frame, forming semi-circular cut out portions at the inner corners of the frame, bending the outer edge of the frame downwardly on a line slightly inside of the notched corner portions, and bending the inner edge of the frame downwardly on a line slightly inside of the circular cut out portions, whereby the vertical walls at the inner and outer corners of the frame are short, and whereby the inner and outer corners of the frame can be formed with

out puckering the material comprising the frame.

3. The method of forming corners for an angular frame composed of angular material, comprising the forming of notched portions at the angle of the frame, making one edge of said notches longer than the other, and bending the longer edge of the notched portion around the corner of the frame to abut the shorter side of the notch, whereby the abutting edges of the notched portions are adjacent the corners of the frame and lie in the same plane to form a flush smooth corner.
- 15 4. The method of making a frame comprising cutting the frame in one piece with an open center from a sheet of material, forming angular notched portions at the exterior corners of the frame, forming semi-circular cut out portions at the interior corners of the frame, and bending the inner and outer edges of the frame downwardly on lines within the said interior and exterior cut out portions.

5. The method of making a frame, comprising cutting the frame in one piece with an open center from a sheet of material, forming angular notched portions at the outer corners of the frame with one side of the notches of a greater length than the other, forming circular cut out portions at the inner corners of the frame, bending the inner and outer edges of the frame downwardly on lines lying inside the inner and outer corner notches to form inner and outer legs for the frame, and bending the longer edge of the angular notched portions around the outer corners of the frame to abut the shorter edges of the notched out portions, whereby the joining edges of the angular notched portions are adjacent the outer corners of the frame, and the inner corners of the frame are rounded.

In testimony whereof, we hereunto affix our signatures.

HENRY MOECKER, JR.
THEODORE THOMPSON.
